HIGH-FREQUENCY IGNITION SYSTEM

Kenneth A. Harmon, Longmeadow, Mass., assignor to Wico Electric Company, West Springfield, Mass., a corporation of Massachusetts

Application March 13, 1951, Serial No. 215,360

1 Claim. (Cl. 322—70)

1

This invention relates to improvements in ignition systems for internal combustion engines and, more particularly, to systems of the general type in which the ignition sparks are produced by discharges from a condenser. The improvements relate primarily to the means for charging the condenser.

In systems of this character, an engine-driven alternator has been used, operating through a full-wave rectifier to charge the condenser. These generators can be designed to function satisfactorily over normal working speeds of the engine. The difficulty is to produce adequate ignition during the relatively slow starting speeds and especially under unfavorable conditions, such as cold weather and a partly depleted battery. Battery-operated induction coils have also been used for the purpose but these are not effective at high engine speeds although they will function well for the starting speeds.

This invention has for its object the provision in an ignition system of the class described of an alternating current generator, which is used as the condenser-charging means, during normal engine operation, and which has a battery-excited field winding, together with a battery-operated vibrator that can be connected into the circuit of the field winding of the generator during starting intervals to produce in such winding a current pulsating at high frequency, while the field magnet is temporarily rendered ineffective for its normal function, whereby to induce in the armature winding the currents necessary for adequate charging of the condenser.

The invention has for another object the control of the vibrator by the same means that controls the starting motor of the engine so that the generator is made to function like a transformer during each starting interval and as a generator during all other intervals of operation.

As contrasted with a generator and battery-operated induction coil used alternately during normal and starting intervals, respectively, of engine operation, this invention uses the one generator, making it function in the normal manner, during normal intervals of engine operation, and disabling it during starting intervals of operation from functioning in the normal manner and utilizing its field and armature windings and magnetic structure as a transformer.

The invention is disclosed for illustrative purposes in the accompanying drawing, in which,

The figure is an electrical diagram of an ignition system embodying the invention.

Referring to the drawing; the ignition system,

2

in general, includes an alternating current generator 1, adapted to be suitably driven by, and in timed relation with, the internal combustion engine, for which the system is to supply ignition; a condenser 2 adapted to be charged by the generator; a full-wave rectifier 3, interposed between the generator and condenser; a spark timer comprising a rotary switch arm 4, adapted to be driven in timed relation with the generator and engine, as by a shaft indicated diagrammatically at 5, and a circular series of contacts 6, adapted to be successively engaged by arm 4; spark-plug transformers one for each contact 6 and each comprising a primary 7 and a secondary 8; and spark plugs 9 one for each contact 6 and engine cylinder.

The generator includes, as relatively rotatable elements, a stationary armature 16 and a rotatable field magnet 11, each constructed of suitable magnetic material. The elements 10 and 11 have a circular series of radial cores 12 and 13, respectively, equally spaced one from another by a predetermined angle. The rotor 11 is driven by shaft 5 in suitable timed relation with the engine (in this case at half engine speed). The number of cores on each element is equal to the number of cylinders in the engine or some multiple of the number of cylinders. On each core 12 is a coil 14 and the several coils are connected together in series so that the voltages in each are added, the whole forming an armature winding. The rotary field magnet is electrically excited and for this purpose is provided with an exciting winding composed of a plurality of coils 15, one on each core 13, and electrically connected in series.

The terminals of the exciting winding are respectively connected by wires 16 and 17 to slip rings 18 and 19, which are rotated by shaft 5, and which are engaged by brushes 20 and 21, respectively. Brush 21 is connected by a wire 22 to the movable magnetic arm 23 of a vibrator 24. This arm 23 carries a contact 25 which is engaged with a stationary contact 26. The latter is connected by a wire 27 to the ground. Bridged across these make and break contacts 25 and 26 is a condenser 28. The other brush 20 is connected by a wire 29 to a fuse 30 and the latter is connected by a wire 31 to one terminal of a manually-operated ignition switch 32, which in turn is connected by a wire 33 to one terminal of a storage battery 34, the other terminal of which is grounded. The make and break contacts 25 and 26 are always engaged when the vibrator 24 is not in operation. Thus, on closing of the ignition switch 32, a current from

battery 34 will flow through the field winding and magnetize the several cores, whereby, when the field magnet is rotating, an E. M. F. is induced in the armature winding in the usual manner.

The terminals of the armature winding are connected by wires 35 and 36 to the input terminals 37 and 38, respectively, of the rectifier 3. The output terminals 39 and 40 of the rectifier are connected by wires 41 and 42 to the condenser 2. The output terminal 39 is grounded. The output terminal 40 is connected by a wire 43 to the rotatable switch arm 4. Each contact 6 is connected by a wire 44 to one terminal of the primary 7 of a spark plug transformer. The other terminal of the primary 7 is grounded. Thus, whenever the arm 4 engages a contact 6 a circuit is completed from the condenser 2 through the primary 7, whereby to induce a high voltage current in the secondary 8, the terminals of which are connected in the usual, or any suitable manner, to a spark plug 9.

The vibrator 24 includes in addition to the make and break contacts 25 and 26, an electromagnet having a core 45 and coil 46 arranged, whenever this coil is energized, to attract the resilient magnetic arm 23 and move it to disengage contact 25 from contact 26. An energizing circuit for the electromagnet is provided and may be traced as follows, from one terminal of battery 34, wire 39, a wire 47, the switch element 48 of a relay, wires 49 and 50, coil 46, a wire 51, arm 23, contacts 25 and 26, and wire 27 to the ground and thus to the other terminal of battery 34. Whenever the switch 48 is closed, the energizing circuit for coil 46 will be closed and the arm 23 will be attracted by the magnetized core 44 to disengage contact 25 from contact 26. As soon as this occurs, the circuit to coil 46 is broken and the contacts 25 and 26 reengage, to be subsequently reengaged and disengaged, the contacts opening and closing at a very rapid rate, say for example at the rate of 100 times per second.

The switch 48 is preferably the switch that controls the motor 52 used to start the engine or one actuated with such switch. The circuit for this motor may be traced as follows, from the ungrounded terminal of battery 34, wires 33 and 47, switch 48, wires 49 and 53 and motor 52 to the ground and thus to the other terminal of the battery. This switch 48 is usually actuated by a relay, comprising a core 54 and coil 55. This coil is energized from battery 34, when a push button switch 56 is actuated. The circuit for coil 55 may be traced as follows, from the ungrounded terminal of battery 34, a wire 57, switch 56, a wire 58, coil 55 and a wire 59 to the ground and thus to the other terminal of the battery. Whenever the circuit to the starting motor 52 is closed, the vibrator 24 will be actuated at high frequency to produce in the field winding a pulsating current, which produces a pulsating magnetic field and induces an E. M. F. in the armature winding. The exciting winding and field winding then function as the primary and secondary, respectively, of a transformer.

In the normal operation of the ignition system, except when starting the engine, the condenser 2 is periodically charged by the generator 1, functioning purely as such, with a rotating field uniformly magnetized by battery current and with alternate polar ends of successive cores 13 of opposite polarity. Each alternation of the generator 1 is used to produce a spark. The condenser 2 receives as many charges per revolution of the

field magnet 11 as there are cores on the latter and on the armature 10. The rectifier 3, by an action analogous to a check valve in a hydraulic system, prevents return flow from the condenser 2 to the generator 1 and thereby the charge is held in the condenser 2 until the spark timer arm 4 engages a contact 6 and allows the condenser to discharge through the primary 7 of a spark plug transformer and cause the induction of a high E. M. F. in the secondary 8 to produce the ignition spark at plug 9. This occurs at the low point of each alternation after time enough has been allowed for the charge to build up in the condenser. The timer arm 4 preferably makes actual engagement with each contact 6. As the arm 4 approaches sufficiently close to a contact 6, the gap between them is ionized and the condenser 2 will then discharge across this gap. There will be but one discharge of the condenser because the ensuing physical engagement of arm 4 and contact 6 will prevent further charging of the condenser. This arm 4 is the spark timing means, even though it also functions to distribute the discharges of the condenser. It is the only means available to effect the timing.

On starting the engine, the closing of the energizing circuit to starting motor 52 also closes the energizing circuit to the coil 46 of the vibrator 24 and the latter is placed in operation, causing the contacts 25 and 26 to make and break at high frequency. This produces a pulsating current in the field winding of the generator 1 and induces currents in the armature winding to charge the condenser 2. During this starting interval, the generator 1 no longer functions in the normal way because its field magnet is temporarily disabled insofar as effective operation is concerned. In place of the constant magnetic flux theretofore produced by battery excitation at constant voltage, a pulsating flux is produced at an extremely rapid rate and charging current may be applied several times to the condenser during the interval in which the rotor moves an angular distance equal to that between successive poles. Thus, the rotating field is rapidly interrupted and its value as a rotating field magnet is temporarily lost. The condenser is then charged by transformer action and very effectively because of the very fact that the generator field magnet is disabled. If, for example, the rotary field magnet consisted of permanent magnets, the flux from these would at times oppose the flux produced by the vibrator in the field winding and interfere with the desired transformer action. With the arrangement of this invention, effective flux reversals at high frequency are obtained without the interference, which would be had if permanent magnets were used as the rotating field of the generator.

Usually, the starting motor will, under optimum conditions, turn the engine at about 200 R. P. M. With a low battery, and/or in cold weather, this rate may be greatly reduced. It is generally required that effective ignition sparks be produced, when the engine is moving at as low a speed as 40 R. P. M. Since the generator turns at half engine speed, the speed limits, during which effective ignition must be produced during the starting interval, are from 100 to 20 R. P. M. With an eight pole generator as shown, from 800 to 160 alternations per minute would be produced or from between 13 and 14 to between 2 and 3 alternations per second. The arrangement of this invention operates, independent of engine speed, at a much higher rate, say 100 alternations

per second and will produce adequate ignition even under the unfavorable very low speed conditions. Charging current will be applied to the condenser several times during the interval that the generator moves through an angle equal to that between successive poles and in which time only one charge would be produced by the generator when functioning in the normal way. The lower the speed, the greater number of times a charging current will be applied in said interval which is what is needed, because if the voltage available from the battery is low, more charging currents will be needed to offset the lowered voltage. This invention will produce around seven charging currents in the interval that the generator would produce one, at an engine speed of say 200 R. P. M., and around thirty three at the low engine speed of 40 R. P. M.. Thus, the condenser may be well charged during starting intervals of engine operation because engine speed is not a factor in the generation of the E. M. F. required and the rotating field magnet of the generator is temporarily rendered ineffective for its normal function.

While the use of a full-wave rectifier is desirable and preferred because it enables all the alternating current generated during normal running operation of the engine to be utilized for condenser-charging, it is not essential to the present invention which relates primarily to the charging of the condenser, during starting intervals of operation of the engine, by means of a pulsating direct current that does not need, or depend on, a rectifier. Thus, a half-wave rectifier might be used without effecting the ignition at starting and, although this would result in a less efficient utilization of the generated alternating current, the lessened efficiency might be compensated for by suitable means.

The invention thus provides as a condenser-charging means, an alternating current generator structure and means for utilizing this structure in two different ways, first, as a generator of alternating current having a battery-excited field magnet producing constant magnetic flux, and second, as a transformer, the field and armature windings respectively functioning as the

primary and secondary windings of the transformer and the field magnet of the generator being disabled, while a high frequency pulsating current is produced in the field winding by a vibrator.

What is claimed is:

The combination with an alternating current generator having relatively rotatable elements, a field winding on one such element, and an armature winding on the other element in which armature winding an electromotive force is generated on relative rotation of the elements, of an electric energizing circuit including said field winding and adapted for connection to a battery, a pair of contacts in said circuit; a vibrator including said contacts, a stationary support for one contact, a resilient support for the other contact tending to hold it engaged with the first contact, said resilient support having a magnetic armature, and an electromagnet operable when energized to attract said armature and move said resilient support to disengage the contacts; an energizing circuit for the electromagnet adapted for connection to the battery in parallel with the field winding and including in series said contacts and electromagnet, and a control switch in the last-named circuit, whereby when the control switch is closed the contacts in the field winding circuit may be opened and closed at a constant and high frequency determined by the resiliency of the support for the movable contact and independently of the speed of relative rotation of said elements to generate an electromotive force in the armature winding.
